United States Patent Office

Des. 176,435
Patented Dec. 20, 1955

176,435

PORTABLE VEHICLE SERVICE STATION OR SIMILAR ARTICLE

Thomas E. Wideman, Sweetwater, Tex.

Application July 21, 1955, Serial No. 37,083

Term of patent 14 years

(Cl. D13—1)

Fig. 1

Fig. 3

Fig. 2

fig. 4

fig. 5

Figure 1 is a top plan view of a portable vehicle service station, showing my new design.

Figure 2 is a front elevational view.

Figure 3 is a rear elevational view.

Figure 4 is a side elevational view, and

Figure 5 is an elevational view of the opposite side of said portable vehicle service station.

I claim:

The ornamental design for a portable vehicle service station or similar article, substantially as shown.
